CHARLES N. SOWDEN, OF GUANTANAMO, CUBA.

DEVICE FOR OPENING ELLIPTICAL SPRINGS.

1,091,975.

Specification of Letters Patent. Patented Mar. 31, 1914.

Application filed July 16, 1913. Serial No. 779,290.

To all whom it may concern:

Be it known that I, CHARLES N. SOWDEN, a subject of the King of Great Britain, and a resident of Guantánamo, Santiago de Cuba Province, Cuba, have invented a new and Improved Device for Opening Elliptical Springs, of which the following is a full, clear, and exact description.

My invention relates to a device to be applied to laminated or leaf springs, such as elliptical or semi-elliptical springs, to separate the leaves or laminations for the purpose of lubricating the spring; and the invention more particularly has reference to 10 that form of device for the indicated purpose, in which opposed wedge members have relative movement toward and from each other, to be entered between the leaves of the spring and withdrawn therefrom.

It is a design of the invention to improve 15 devices of the indicated character in various particulars, to the end that efficiency in operation may be promoted, as well as economy of manufacture and simplicity of 20 adjustment and operation.

The invention will be particularly explained in the specific description following.

Reference is to be had to the accompanying drawings forming a part of this specification, in which similar characters of reference indicate corresponding parts in all the 30 views.

Figure 1 is a side elevation of a device embodying my invention, showing the same 35 applied to a spring shown in cross section, with the wedge elements about to be entered between the laminations of the spring; Fig. 2 is an end view; Fig. 3 is a view similar to Fig. 1, showing the parts in position after 40 the wedges have been given a relative movement toward each other; Fig. 4 is a cross section on the line 4—4 of Fig. 3; Fig. 5 is a partial longitudinal vertical section; and Fig. 6 is a developed view of the cam faces 45 for giving one of the jaws a movement toward or from the opposite jaw.

My improved device comprises a frame 10 of general U-shape, one end of which is in the form of a forked jaw 11, the terminals 50 12 of which extend inwardly and are wedge-shaped. The opposite arm 13 of the U-frame has a fixed head 14 of tubular form constituting a bearing to receive the cylindrical stem 15 of a movable jaw 16, said stem hav-

ing at its outer end a lever handle 17, for 55 turning the jaw in the bearing 14. The jaw 16 is formed by the front end of the stem 15 and an annular exterior portion 16^a, which in practice, is formed as a separate ring which is shrunk or otherwise secured in 60 position after the stem 15 has been moved inwardly into the bearing 14, with the inner end projected beyond the adjacent end of the said bearing. The said movable jaw 16 has a wedge point 18 which preferably is of 65 conical form and disposed in a line centrally of the spaced wedge members 12 of the fixed jaw 11.

In order to give the wedge elements a relative movement toward or from each other, cam surfaces are produced on the opposed faces of the bearing 14 and the rear of the jaw 16. The cam faces on the said bearing and jaw present opposite inclines, the inclines of each member defining opposite 75 V-shape formations, the dimensions of which are preferably such that a quarter turn of the lever 17 and the jaw 16 will cause the wedge elements 12 and 18 to approach each other to an extent to separate two adjacent 80 laminations *a* of a spring *A* sufficiently to permit of the introduction of a lubricant therebetween. This will be clear by reference to Figs. 1, 3 and 6, from which it will be seen that a single incline 20 extends one 85 quarter of the circumference of the jaw 13, and that a single incline 19 on the bearing 14 is correspondingly formed.

I make provision for holding the jaw 16 in a given projected position, by preventing 90 a retrograde movement of the inclines 20 thereof on the opposed inclines 19 of the bearing 14. To effect the purpose the jaw is made to interlock with the bearing at intersections of opposed inclines; thus at 21 on 95 the jaw at intersections of two converging inclines 20, an edge or tapered terminal is presented in the direction of the cam surfaces 19 of the bearing, and similarly two adjacent inclines 19 on the bearing converging in the direction of the jaw, present a corresponding tapered formation with the taper in the direction of the jaw. I produce in the bearing, at the forward tapered portions thereof, depressions 22 to receive an 105 edge portion 21, upon a quarter turn of the jaw 16 in either direction, thereby producing an interlocked engagement between the

jaw and the bearing, sufficient to prevent accidental turning of the jaw, but an engagement that may be readily overcome by the deliberate turning of the lever 17 by the user.

To better accommodate the device to springs of varying widths, provision is made for adjusting the wedge point or center 18, relatively to its jaw 16, by permitting the 10 axial movement of the center in the stem 15, and to that end, the wedge 18 is formed separately from the jaw 16, and the stem 24 of said wedge is grooved, as at 25, at opposite sides, the grooves being intersected by 15 transverse fastening pins 26, that are passed through the stem 15, at opposite sides of the stem 24. The groove 25 has a width, considered lengthwise of the stem, considerably greater than the diameter of the pins 26, so 20 that an axial movement of the stem 24 may be effected relatively to the said pins.

The axial movement of the wedge 18 may be effected by a set screw 23, which is threaded axially in the stem 15, to constitute a follower and backing for the stem 24. By turning the set screw 23 backwardly or forwardly, the wedge 18 may be projected more or less beyond the face of the jaw 16, to maintain the desired adjustment of the parts and 25 insure that a quarter turn of the jaw will advance the wedge 18 the proper distance for the separation of the laminations of the spring.

It will be observed that the inclines of the 30 cam surfaces on both the movable jaw and its supporting arm present on said jaw and arm alternate V-shaped recesses and tapering projections, the sides of which recesses and projections constitute intersecting elements of 35 double right and left threads, and also that the terminals of the projecting members on the cam faces of the arm and jaw, when in line with each other and interlocked by the engagement of the tapering edge 21 with an 40 opposite depression 22, may be moved from the interlocked position and be permitted to recede axially by a turn in either direction; similarly the movable jaw may be advanced 45 from the rearward position by a turning of the said jaw in either direction.

Having thus described my invention, I claim as new and desire to secure by Letters Patent:

1. A device of the character described, 50 comprising a frame having arms, one of which constitutes a fixed jaw, said jaw having a wedge member disposed in the direction of the opposite arm, and a movable jaw having a stem axially movable and adapted 55 to turn in said opposite arm, the movable jaw having a wedge member disposed in the direction of the opposite arm, the said stem extending through its supporting arm and provided at the end opposite the wedge member with a handle lever to rock the same, the 60

opposed faces of the jaw and its supporting arm having cam faces formed by opposite inclines presenting on said jaw and arm alternate V-shaped recesses and tapering projections, the sides of which recesses and projections constitute intersecting elements of double right and left threads, the terminals of the projecting members on the cam faces of the arm and jaw presenting co-acting locking formations, so that the jaw will be locked 70 against retrograde movement when its cam members are directly opposite corresponding members on the arm.

2. A device of the character described, comprising a frame having arms, one of which constitutes a fixed jaw, said jaw having a wedge member disposed in the direction of the opposite arm, and a movable jaw mounted for axial and turning movement in the said opposite arm, the opposed faces of 80 the movable jaw and its supporting arm having cam faces formed by opposite inclines presenting on said jaw and arm V-shaped recesses and tapering projections, the sides of which recesses and projections constitute intersecting elements of double right and left threads.

3. A device of the character described, comprising a frame having arms, one of which constitutes a fixed jaw, said jaw having a wedge member disposed in the direction of the opposite arm, and a movable jaw mounted for axial and turning movement in the said opposite arm, the opposed faces of the movable jaw and its supporting arm having cam faces formed by opposite inclines presenting on said jaw and arm V-shaped recesses and tapering projections, the sides of which recesses and projections constitute intersecting elements of double right and left threads, the terminals of the projecting members on the cam faces of the arm and jaw presenting co-acting locking formations so that the jaw will be locked against retrograde movement when its cam members are 90 directly opposite corresponding members on the arm, but is capable of receding when turned in either direction from the engaged position of the projecting members.

4. A device of the character described, comprising a frame having arms one of which is formed with a wedge member projecting in the direction of the opposite arm, a jaw mounted to rock in said opposite arm and to move axially therein, means for moving the said jaw axially upon a turning movement of the same, means for rocking the movable jaw to move it axially, a wedge element projecting from the face of the movable jaw and having a stem extending axially in 100 said jaw, a set screw in the movable jaw for adjusting the wedge member to give more or less projection beyond the face of the movable jaw, and pins extending transversely 105 of the movable jaw, the stem of the wedge 110

member being recessed, permitting a movement of the wedge element relatively to the pins in response to movements of the set screw.

5. In a device of the class described, in combination with spreading wedges, actuating devices presenting opposed serrations complementary to each other and adapted to operate the spreading wedges by a turning

movement of said serrations in either direction relatively to each other. 10

In testimony whereof I have signed my name to this specification in the presence of two subscribing witnesses.
